TYPOGRAPHICAL COMPOSING MACHINE

John C. Packard, Paterson, N. J., assignor to
Mergenthaler Linotype Company, a corpora-
tion of New York

Application August 15, 1939, Serial No. 290,165

20 Claims. (Cl. 199—27)

This invention relates to typographical composing machines of the general organization represented in U. S. Letters Patent to O. Mergenthaler No. 436,532, wherein circulating matrices are released from a storage magazine in the order in which their characters are to appear in print and then composed in line, the composed line transferred to the face of a slotted mold, the mold filled with molten metal to form a type bar or slug against the matrices which produce the type characters thereon, and the matrices thereafter returned through a distributing mechanism to the magazine from whence they started.

In these machines, the matrices, as they are released from the magazine, descend by gravity through a channeled raceway and fall onto the upper stretch of an inclined conveyor belt which delivers them, one after another, to a chute or throat whereby they are directed into an assembling elevator. As the matrices enter the assembling elevator, they are stacked side by side in line, under the influence of a rapidly rotating star wheel, against an upstanding finger or line resistant secured to one end of a yielding assembler slide. The star wheel is mounted on a fore-and-aft shaft and is rotated thereby through the medium of a power-driven gear and an interposed friction clutch, which latter is maintained under spring tension so that in case the rotation of the star wheel is abnormally resisted for any reason it will yield or slip to allow the power driven pinion to rotate freely until the obstruction to the rotation of the star wheel is removed. With such an arrangement for rotating the star wheel, adjustments in the tension of the spring must be made from time to time to keep it at a desired value because, if the tension is too little, the clutch will slip and the matrices will not be forced into the assembling elevator in the proper manner. On the other hand, if the tension of the spring is too great, the clutch will not slip when the rotation of the star wheel is abnormally resisted and thus cause considerable damage to the star wheel, the matrices, the power driven gear and/or the assembling elevator. Heretofore, such adjustments in the tension of the spring had to be made at the rear of the machine and required considerable time and effort on the part of the operator.

In accordance with the present invention, a star wheel assembly is provided whereby an adjustment in the tension of the clutch spring is easily and simply made by the operator without leaving his position at the front of the machine. To this end, the clutch spring is mounted on the

rear end of an adjustable spindle threaded through a fore-and-aft sleeve on which the star wheel is mounted at the front end thereof, the tension of the spring being dependent on the position of the spindle in the sleeve. When the machine is operating, the spindle and the sleeve are locked against relative movement so as to rotate as one, but when it is desired to change the tension of the spring to increase or decrease the power of the clutch, the machine is stopped, the spindle and the sleeve are unlocked, and the star wheel then turned manually to rotate the sleeve with respect to the spindle. When the sleeve is rotated in one direction, the spindle is caused to move rearwardly therethrough to relieve the tension of the spring and so decrease the driving power of the clutch; whereas, when the sleeve is rotated in the opposite direction, the spindle is caused to move forwardly therethrough to compress the spring and so increase the driving power of the clutch. In this way, such adjustments are not only quickly and conveniently accomplished but the "feel" of the frictional resistance as it varies during the adjustment enables the operator to determine at once and with a high degree of accuracy the drive he requires at the time. After the adjustment has been made, the spindle and sleeve are again locked together and the machine re-started for operation in the usual manner.

In the accompanying drawing, the invention has been shown merely in preferred form and by way of example, but obviously many changes and variations may be made therein and in its mode of application which will still be comprised within its spirit. It should, therefore, be understood that the invention is not limited to any specific form or embodiment, except insofar as such limitations are specified in the claims.

Referring to the drawing:

Fig. 1 is a front elevation of the assembling mechanism with a portion broken away to expose the star wheel;

Fig. 2 is an enlarged side view, partly in section, of the star wheel assembly drive;

Fig. 3 is an enlarged vertical section through the improved star wheel assembly; and

Fig. 4 is a detail vertical section taken on the line 4—4 of Fig. 2 showing the manner in which the disk 27 is mounted on sleeve 18.

In the operation of the machine, the matrices 10 are released from a storage magazine (not shown) and pass downwardly through a channeled raceway 11 onto a constantly driven inclined belt 12 which discharges them one after

another in the order of their release into a throat or chute 13 leading to the assembling elevator 14. Here they are composed in line against an upstanding finger 15 of a line resistant slide 16 under the influence of a rapidly rotating star wheel 17 which crowds them forwardly against the end of the line and at the same time advances the latter to admit the next or following matrix.

In accordance with the present invention, the star wheel 17 is secured to a fore-and-aft sleeve 18 at the front end thereof. The sleeve 18 is rotatably mounted in a bushing 19 which is maintained in fixed position in the assembler frame 20 by a set screw 21. A spindle 22 is threaded through the sleeve 18 and protrudes beyond the rear end thereof where it is provided with an enlarged portion 23 having a retaining collar 24. Under normal conditions, the sleeve 18 and the spindle 22 are locked against relative movement by means of a jam stud 31 threaded into the forward end of the sleeve and against the front end of the spindle. The sleeve 18 is reduced at its rear end, and on this reduced rear end a gear 25 is loosely mounted behind a friction disk 27 keyed to the sleeve (see Fig. 4) adjacent an annular shoulder 26 which is formed by the sleeve being so reduced. The gear 25 is rotated continuously during the operation of the machine through the usual power operating devices including the gear 28 which is in mesh therewith. A tension spring 29, positioned about the enlarged portion 23 on the rear end of the spindle 18 with its rear end banking against the retaining flange 24 and its front end banking against a rearwardly projecting hub portion 25^a of the gear, tends to force the gear 25 forwardly along the sleeve 18 and so maintains it in engagement with the friction disk 27. The amount of friction thus caused between the gear 25 and the friction disk 27 depends on the tension of the spring 29 and hence on the position of the spindle 22 in the sleeve 18. When the tension of the spring 29 is properly regulated, the gear 25, the disk 27, the spring 29, the sleeve 18, the spindle 22, and the star wheel 17 all rotate as a unit and in the manner intended. As will be seen in Fig. 2, the opposite end portions of the spring 29 are flattened to increase the area of its frictional contact with the hub portion 25^a of the gear 25 and the collar 24 of the spindle 22.

In the event an adjustment is required in the tension of the spring 29, the machine is stopped in the usual way (by shifting the driving belt 9 onto the idler pulley 8, see Fig. 2), the assembler cover plate 33 is swung downwardly about its axis 34 to expose the star wheel 17, the jam stud 31 is backed off by means of a screwdriver, it being provided with a slot 32 at its outer end for this purpose, and the star wheel 17 is rotated manually. When the star wheel 17 is thus rotated, the sleeve 18 and the friction disk 27 rotate in unison therewith, but the gear 25 (which, it will be remembered, is loosely mounted on the sleeve) is held stationary by the inertia of its driving mechanism, then at rest. Since the gear 25 is held stationary under these conditions, and since the spring 29, as above described, at one of its ends frictionally engages the hub portion 25^a of the stationary gear 25 and at its other end frictionally engages the collar 24 on the spindle 22, the latter is also held against rotation, with the result that it is caused to move inwardly or outwardly through the sleeve 18 to decrease or increase the tension of the spring 29, depending on the direction in which the sleeve 18 is rotated by

the star wheel 17, and thus varying the driving power of the clutch as desired. During the adjusting operation, it may be mentioned that the thrust of the spring 29 will always be sustained by the shoulder 26 irrespective of the direction in which the sleeve 18 is rotated (the gear 25 and friction disk 27 both being free to slide along the reduced rear end portion of the sleeve 18), the distance between a collar 30 formed on the sleeve 18 and the shoulder 26 being slightly greater than the length of the bearing bushing 19 to allow the clearance necessary for this condition to obtain. After the desired adjustment in the tension of the spring 29 has been made, the jam stud 31 is threaded inwardly against the end of the spindle 22 to prevent relative movement between it and the sleeve 18, and the machine is again ready to be started for continued operation (by shifting the driving belt 9 onto the live pulley 7).

Having thus described my invention, what I claim is:

1. In or for a typographical composing machine, assembling mechanism including, in combination, a rotatable star wheel, a clutch for driving said wheel, and means operable from the front of the machine for adjusting the clutch to increase or decrease the driving power thereof.

2. In or for a typographical composing machine, assembling mechanism including, in combination, a rotatable star wheel, a friction clutch for driving said wheel, a spring controlling the frictional power of said clutch, and adjustable means operable from the front of the machine for increasing or decreasing the tension of said spring.

3. In or for a typographical composing machine, assembling mechanism including, in combination, a rotatable star wheel, a clutch for driving said wheel when the machine is operating, and adjustable means for regulating the driving power of the clutch, said means being operable from the front of the machine when the machine is at rest.

4. In or for a typographical composing machine, assembling mechanism including, in combination, a rotatable star wheel, a clutch for driving said wheel when the machine is operating, and means operable by the manual rotation of the star wheel when the machine is at rest for adjusting the clutch so as to increase or decrease the power thereof as desired.

5. In or for a typographical composing machine, assembling mechanism including, in combination, a rotatable star wheel, a friction clutch for driving said wheel, a spring controlling the frictional power of said clutch, and adjustable means operable by the independent rotation of the star wheel for increasing or decreasing the tension of said spring as desired.

6. In or for a typographical composing machine, assembling mechanism including, in combination, a rotatable star wheel, a clutch for driving said wheel, and an adjustable fore-and-aft spindle operable from the front of the machine for regulating the driving power of said clutch.

7. In or for a typographical composing machine, assembling mechanism including, in combination, a rotatable star wheel, a clutch for driving said wheel, a spring controlling the power of said clutch, and an adjustable fore-and-aft spindle operable from the front of the machine for increasing or decreasing the tension of the spring as desired.

8. In or for a typographical composing machine, assembling mechanism including, in combination, a rotatable star wheel, a clutch for driving said wheel, an adjustable fore-and-aft spindle for regulating the power of said clutch, and a rotatable sleeve operable from the front of the machine for effecting the adjustment of the spindle as desired.

9. In or for a typographical composing machine, assembling mechanism including, in combination, a rotatable star wheel, a clutch for driving said wheel, a spring controlling the power of said clutch, an adjustable spindle for increasing or decreasing the tension of said spring, and a rotatable sleeve operable from the front of the machine for effecting the adjustment of the spindle as desired.

10. In or for a typographical composing machine, assembling mechanism including, in combination, a rotatable star wheel, a clutch for driving said wheel, an adjustable fore-and-aft spindle for regulating the power of said clutch, and a rotatable sleeve operable through the star wheel for effecting the adjustment of the spindle as desired.

11. In or for a typographical composing machine, assembling mechanism including, in combination, a rotatable star wheel, a clutch for driving said wheel, a spring controlling the power of said clutch, an adjustable fore-and-aft spindle for increasing or decreasing the tension of said spring, and a rotatable sleeve operable through the star wheel for effecting the adjustment of the spindle as desired.

12. In or for a typographical composing machine, assembling mechanism including, in combination, a rotatable star wheel, a clutch for driving said wheel, an adjustable fore-and-aft spindle for regulating the power of the clutch, a rotatable sleeve operable from the front of the machine for effecting the adjustment of the spindle, and means movable to active position to lock the spindle against adjustment when the machine is operating and to inactive position to permit the adjustment of the spindle when the machine is at rest.

13. In or for a typographical composing machine, assembling mechanism including, in combination, a rotatable star wheel, a friction clutch for driving said wheel, an adjustable fore-and-aft spindle for regulating the driving power of the clutch, a rotatable sleeve having a screw-thread engagement with the spindle, and means movable to active position to lock the sleeve and spindle against relative movement and to inactive position to permit adjustment of the spindle by means of the sleeve.

14. In or for a typographical composing machine, assembling mechanism including, in combination, a rotatable star wheel, a power driven gear, a friction disk, a spring for maintaining said disk and gear in frictional engagement to bring about the rotation of said wheel, and adjustable means operable from the front of the machine for increasing or decreasing the tension of the spring as desired.

15. In or for a typographical composing machine, assembling mechanism including, in combination, a fore-and-aft rotatable sleeve, a star wheel secured to said sleeve at the front end thereof, a power driven gear loosely mounted on said sleeve at the rear end thereof, a friction disk fixed to said sleeve and arranged alongside said gear, a spring for maintaining said gear and disk in frictional engagement to bring about the ro-

tation of the star wheel, and adjustable means operable from the front of the machine for increasing or decreasing the tension of said spring as desired.

16. In or for a typographical composing machine, assembling mechanism including, in combination, a fore-and-aft rotatable sleeve, a star wheel secured to said sleeve at the front end thereof, a power driven gear loosely mounted on said sleeve at the rear end thereof, a friction disk fixed to said sleeve and arranged alongside said gear, an adjustable spindle positioned in said sleeve, a spring for maintaining said gear and disk in frictional engagement to bring about the rotation of the star wheel, and means adapted by the rotation of the sleeve relatively to the spindle for effecting the adjustment of the latter so as to increase or decrease the tension of the spring as desired.

17. In or for a typographical composing machine, assembling mechanism including, in combination, a fore-and-aft rotatable sleeve, a star wheel secured to said sleeve at the front end thereof, a power driven gear loosely mounted on said sleeve at the rear end thereof, a friction disk fixed to said sleeve and arranged alongside said gear, a spindle threaded through said sleeve, a spring for maintaining said gear and disk in frictional engagement to bring about the rotation of the star wheel, and means operable from the front of the machine for adjusting the spindle in the sleeve to increase or decrease the tension of the spring as desired.

18. In or for a typographical composing machine, assembling mechanism including, in combination, a fore-and-aft rotatable sleeve, a star wheel secured to said sleeve at the front end thereof, a power driven gear loosely mounted on said sleeve at the rear end thereof, a friction disk fixed to said sleeve and arranged alongside said gear, a spindle threaded through said sleeve, a spring for maintaining said gear and disk in frictional engagement to bring about the rotation of the star wheel and adjustable as to tension according to the position of the spindle in the sleeve, and means for locking and unlocking said spindle and sleeve against relative movement, whereby the manual rotation of the star wheel when said spindle and sleeve are unlocked will adjust the spindle in the sleeve to increase or decrease the tension of the spring as desired.

19. In or for a typographical composing machine, assembling mechanism including, in combination, a fore-and-aft rotatable sleeve, a star wheel secured to said sleeve at the front end thereof, a power driven gear loosely mounted on said sleeve at the rear end thereof, a friction disk fixed to said sleeve and arranged alongside said gear, a spindle threaded through said sleeve and presenting rearwardly of said gear an enlarged cylindrical portion with an annular collar, a coil spring surrounding the enlarged portion of the spindle, said spring bearing at one end against the annular collar on the enlarged portion and at its opposite end against the power driven gear to hold the latter in frictional engagement with the friction disk fixed to the sleeve, and means for locking the sleeve and spindle together to rotate as one when the machine is in operation, said means being releasable when the machine is at rest to permit the fore-and-aft adjustment of the spindle by a relative rotation of the sleeve to vary the tension of the spring as desired.

20. In or for a typographical composing machine, assembling mechanism including, in combination, a fore-and-aft rotatable sleeve, a star wheel secured to said sleeve at the front end thereof, a power driven gear loosely mounted on said sleeve at the rear end thereof, a friction disk fixed to said sleeve and arranged alongside said gear, a spindle threaded through said sleeve and presenting rearwardly of said gear an enlarged cylindrical portion with an annular collar, a coil spring surrounding the enlarged portion of the spindle, said spring bearing at one

end against the annular collar on the enlarged portion and at its opposite end against the power driven gear to hold the latter in frictional engagement with the friction disk fixed to the sleeve, and a jam stud also threaded into the sleeve forward of the spindle and operable to lock the spindle to the sleeve when the machine is in operation and to unlock the spindle from the sleeve when the machine is at rest, as and for the purpose described. 5 10

JOHN C. PACKARD.
